TIMING APPARATUS

Wilson M. Powell and Albert W. Hughes, Berkeley, Calif., assignors to the United States of America as represented by the United States Atomic Energy Commission

Application September 28, 1949, Serial No. 118,302

4 Claims. (Cl. 161—1)

1

This invention relates to a new and improved timing apparatus and more especially to a timing apparatus suitable for controlling the several closely spaced sequential events inherent in the operation of cloud chambers. In its broader aspects, however, the invention may be employed in connection with the timing of operations of any suitable combination of associated apparatus and thus is not limited exclusively to cloud chamber usages.

As is known, the operation of cloud chambers, when employed to provide photographic records of ionizing events resulting from controlled operation of particle accelerators, requires exceptionally rapid and accurate timing means. Conventional timing means often are used for the slower and preliminary phases of preparation of the chamber prior to reception of the ion beam, as for example the giving of a warning signal, the resetting of a clearing field, the resetting of a generator circuit or the preliminary slow expansion of the chamber volume. However, when these preliminary preparations have been completed a fast and dependable timing means, commonly called the "cloud chamber fast timer," is needed to achieve optimum results from the chamber and its associated particle accelerator which provides the particles responsible for the ionizing events. Moreover, due to the lapse of time required for the preliminary preparations, as well as delays caused by other factors, it is not feasible to have the fast timing means operating continuously. As a consequence, special design features permitting quick starting and stopping, low moments of inertia and the like are demanded in the construction of such means. The present invention therefore has as an object the provision of a new and improved fast timing means suitable for controlling the final stages of cloud chamber operations.

A second object is to provide a new and improved intermittently operable timing means for jointly controlling a cloud chamber and a particle accelerator.

Another object is to provide a timing means having an improved mechanical driving structure affording intermittent rotation of a timer shaft.

Another object is to provide a timing means having a plurality of adjustable switch elements adapted to provide positively spaced functioning thereof.

A further object is to provide a timing means having relatively small inertia of moving parts.

Other objects and advantages will become more

2

apparent as the description proceeds when considered in conjunction with the accompanying drawings in which

Figure 1 is a diagrammatic view illustrating one arrangement of the timing means with respect to the cloud chamber, particle accelerator and camera;

Fig. 2 is a perspective view of the timing means showing the drive mechanism therefor;

Fig. 3 is a sectional view of a portion of the timing means taken along the vertical axis of the timer shaft; and

Fig. 4 is an end view showing the motor mounting with the surrounding housing for the structure being shown in section.

Referring first to Fig. 1, one utilization is shown by means of which the timer 10 may control the sequence of operation of the clearing field of a cloud chamber 11, the fast expansion means 12 of said chamber, the oscillator 13 of a particle accelerator 14, such as a cyclotron, the arc pulse means 15 of said particle accelerator, the camera means 16 and the necessary stopping means for the timer itself. As will be apparent, appropriate conductors, sources of electrical current, actuating devices dependent upon impulses from timer 10, and the like, forming no part of the present invention, may be employed as desired for carrying out the control of the chamber and accelerator. By proper calibration of the timer in a manner later to be disclosed, these several events may be controlled so as to be effected within a total elapsed time of approximately 0.25 second. As will further be apparent to those skilled in the art, conventional cloud chambers, cameras and particle accelerators may be employed in connection with our invention and no detailed description thereof is required for a full understanding of our improved apparatus. In addition, it will be further understood that other timing apparatus may be employed in connection with the preliminary operations of these several units of the combination prior to the control exerted by timer 10 for the final, fast operation of the combined structures.

As shown in Figs. 2 and 3, the timer means 10 may be constructed as a compact unit having a vertically disposed front wall 20 and rear wall 21. At one end of said walls a cross member 22 provides a bearing surface 23 in which one end of the rotatable main timer shaft 100 is journaled. Adjacent the other end of said walls a second cross member 25 is located between said walls thus providing a second mounting in which the shaft may be journaled and resulting in an

open framework upon which the several elements of the timing apparatus may be positioned for easy adjustment and maintenance.

For the purpose of mounting the driving connection from a suitable motor to shaft 100, a platform including upper and lower plates 30 and 31 respectively is provided. At one end each plate is securely affixed to cross member 25 while at a point spaced inwardly from the other end of each plate, a spacer 24 is located serving as a further bearing for said shaft as well as a braking abutment therefor. The lower plate 31 preferably extends farther beyond said spacer than does its companion upper plate 30 and said lower plate terminates in a bifurcated portion 32 through which a suitable pin 33 may extend for a purpose later to become apparent.

Mounted in cantilever fashion upon the side of cross member 25 near rear wall 21, as by means of an appropriate bracket 36, is a small electric motor 37, preferably of the synchronous type and connected by any suitable means (not shown) to a source of power. Motor 37 is provided with a suitable gear reduction means including a driven gear 38 adapted to mesh at all times with a gear 39. During operation of the cloud chamber and the particle accelerator, motor 37 is permitted to run continuously thus effecting a continuous rotation of gears 38 and 39. By a suitable gear ratio any desired speed of rotation may be imparted to the timer shaft 100, one speed which has been found to be satisfactory being that of 120 revolutions per minute.

In view of the intermittent usage required by cloud chamber operation, a clutch and braking arrangement best shown in Fig. 3 is adapted for the intermittent application of the power from motor 37 to shaft 100. Spacer 24 is provided on one side with a circular aperture into which extends a rotatable sleeve 40 rigidly affixed to gear 39 and serving to support said gear in meshed rotation with gear 38. A conventional ball bearing 41 may be disposed between spacer 24 and gear 39 for transmitting axial thrust forces. At its other side spacer 24 may have a conical braking surface 42 against which a complementary shaped braking element 43 is adapted to bear at predetermined intervals. As shown, sleeve 40 at no time is in contact with braking element 43. Element 43 is rigidly affixed to a reciprocable stub shaft 50 having a slot 51 in one end thereof and into which a projection 52 in the end of timer shaft 100 projects at all times. Moreover, shaft 50 is of such size and weight as to have comparatively little inertia in rapid starting and stopping. An adjustable bushing 54 mounted in cross member 25 provides one bearing surface for a compression spring 55 while a washer 56 resting against a ball bearing 57 in turn positioned against the rear wall of braking element 43 provides a second bearing surface for said spring. As will now be apparent from Fig. 3, spring 55 normally holds the braking member 43, the stub shaft 50 and the engaged timer shaft 100 in stationary position and a positive controlled action is required to effect rotation of these shafts.

One means for effecting the desired rotation may be provided by a conventional solenoid 60 suitably mounted upon top plate 30 of the platform and having a core 61 attached to the movable shaft actuating arm 62. This arm is pivotally mounted upon pin 33 at its lower end and is connected to the core 61 at its upper end. Suitable electrical connections, not shown, serve to actuate the solenoid core and thereby to move the arm 62 with appreciable leverage at the de-

sired time. A tension spring 63 may be employed to hold arm 62 in ready position. As an example, a lead from the last to operate of switches 110 may be used to interrupt the electrical connection to the solenoid. Adjacent the lower portion of arm 62 an adjustable buffer means 64 is positioned and is adapted to be adjusted when desired, as by a suitable set screw 65. As said arm 62 moves inwardly of the platform, said buffer means contacts the outer end of stub shaft 50 and quickly moves it inwardly, thus effecting a release of the braking means 43 from contact with surface 42 and permitting rotation of the engaging shafts.

As shown in Fig. 3 the rotating gear 39 is provided with a conical cavity 70 with which a complementary conical surface 71 on the end of stub shaft 50 is adapted to engage. Upon actuation of arm 62 as above described this portion of the stub shaft engages with the gear 39 and since a simultaneous release of the braking means has occurred, shaft 50 and shaft 100 instantly begin to rotate.

The thus described means for effecting rotation of shaft 100 contributes in large measure to the realization of the objects of our invention, as now will be found from the following description.

Upon timer shaft 100 a plurality of separately adjustable control groups are mounted, in this case shown as six. Since each such group preferably is identical in structure with the other groups, a description of one is considered sufficient. Referring now to Figs. 2 and 3, it will be noted that the several control groups are mounted side by side in closely spaced relation upon shaft 100 beginning immediately adjacent the cross member 25 of the mounting framework and extending to a point immediately adjacent the outer cross member 22. As a result, a compact structure is provided and both the length and inertia of drive shaft 100 is thus further reduced.

Surrounding shaft 100 and independently movable with respect thereto is a switch supporting means, here shown as a circular plate 101 provided with a circumferential rim 102 adapted to bear indicia of time intervals. Plate 101 preferably is provided with a hub section 103 adapted to be loosely supported upon the rotatable timer shaft 100. As will be apparent, if the small amount of friction caused by resting the plate 101 upon the timer shaft tends to hamper the quick starting and stopping of the shaft, such plate may conveniently be entirely supported for adjustable movement upon walls 20 and 21 without departing from the invention. In some cases, however, a small amount of friction is useful in controlling the movement of the low inertia timer shaft and the arrangement as shown has been found to be satisfactory in such cases. To the hub section 103 a worm gear 104 is rigidly affixed and is adapted to mesh with a rotatable worm 105 mounted upon shaft 103. This shaft may be mounted at one end in front wall 20 and at the other end in rear wall 21 and is adapted to be turned as by means of a knob 107. Any suitable means for preventing play or back-lash in worm 105 may be used, such as a compression spring, not shown, located adjacent rear wall 21.

Rigidly affixed to one side of plate 101 at an appropriate height is a conventional microswitch element 110 having connections, not shown, leading to a unit to be controlled. For example, the switch 110 herein shown may normally be the first to operate and may conveniently lead to the cloud chamber clearing field apparatus as di-

grammatically shown in Fig. 1. Depending from switch 110 is a contact arm 111 and actuating roller 112 therefor so arranged that when the arm is lifted the desired action of switch 110 will occur.

Cooperating with the roller 112 is a circular, relatively thin and light weight cam plate 115 rigidly affixed to shaft 100 by any suitable means and bearing one or more light weight adjustable members such as the lugs of "dogs" 116. These members may be securely adjusted in place upon the circumference of plate 115, in the path of contact with roller 112, by means of set screws or similar fastening means. Since lugs 116 may be positioned at any point on the circumference of cam plate 115 and since shaft 100, in the example given, may rotate at a speed of twice per second, it will be obvious that the operation of the microswitch can be calibrated to extremely small intervals of time. Upon the rim 102 of the corresponding plate 101 a scale 113, preferably reading in hundredths of a second intervals, is placed and may be viewed from the exterior of front wall 20 as through the transparent closure 114.

As will be apparent, any desired number of the above-described control groups may be mounted side by side upon timer shaft 100 and the leads from the switches 110 thereof may be connected to the apparatus desired to be controlled in conjunction with the cloud chamber operation. In so assembling the apparatus the indicia upon the several plates 101 preferably are positioned along a reference line and the lugs 116 placed upon plates 115 along the same or an equivalent reference line. After determining the units to be controlled, the relative timing therebetween and the sequence of control, the several plates 101 are turned by means of knobs 107 until the proper time intervals are shown by scales 113 against the proper reference line. Thereafter upon rotation of shaft 100 the desired sequence and timing of operation of switches 110 will occur. Normally the last switch 110 to operate serves to interrupt the current to solenoid 60 so that the shaft 100 is brought quickly to rest as heretofore described. After the solenoid 60 is inactivated and the timer shaft comes to rest a variable interval of time may elapse before the apparatus is again used. Accordingly, a separate connection of any conventional nature, such as a push button, not shown, may be employed to energize solenoid 60.

Whereas the apparatus as above described may be employed for many usages it will be apparent that on occasion additional features may be desired without changing in any way the essential nature of the invention. For example, the timing apparatus as a unit may be fitted, after adjustment of the control groups, into various types of dust tight enclosures provided with the essential apertures for electrical leads. As shown in Fig. 4 one such enclosure may be fitted against the rear portion of wall 20.

Having thus described our invention with respect to one embodiment thereof, it will be apparent that numerous modifications may be made within the spirit and scope of the invention. Therefore, it is not desired to limit the invention to the exact details shown except insofar as they may be defined in the following claims.

What is claimed is:

1. In a timing apparatus having an intermittently rotatable timer shaft, cam means affixed to said shaft and a switch adjustable in position with respect to said cam and operable thereby,

the improvement comprising, means for controlling rotation of said shaft and including, a constant speed motor having a shaft driving gear adapted to rotate continuously, a reciprocable

- 5 stub shaft in axial driving engagement with said timer shaft, a support for said stub shaft, a braking member on said stub shaft adapted to engage said support in one position of the stub shaft, means normally holding said stub shaft in braking position, a clutch member on said stub shaft adapted to engage the shaft driving gear in a second and axially displaced position of the stub shaft and intermittently operable clutch engaging means adapted to force the stub shaft into engagement with the shaft driving gear and to release the braking member from engagement with the support.

2. In a timing apparatus having an intermittently rotatable timer shaft, cam means affixed to said shaft and a switch adjustable in position with respect to said cam and operable thereby, the improvement comprising, means for controlling rotation of said shaft and including, a constant speed motor having a shaft driving gear

- 20 adapted to rotate continuously, a reciprocable stub shaft in axial driving engagement with the timer shaft, a support for said stub shaft, a braking member on said stub shaft adapted to engage said support in one position of the stub shaft, a direct acting compression spring normally holding said stub shaft in braking position, a clutch member on said stub shaft adapted to engage the shaft driving gear in a second and axially displaced position of the stub shaft, a solenoid, and intermittently operable clutch engaging means connected to said solenoid and operable to force the stub shaft into engagement with the shaft driving gear and to release the braking member from engagement with the support.

3. In a timing apparatus having an intermittently rotatable timer shaft, cam means affixed to said shaft and a switch adjustable in position with respect to said cam and operable thereby, the improvement comprising, means for controlling rotation of said shaft and including, a constant speed motor, a centrally bored rotary element in continuously driven relationship with said motor, a reciprocable stub shaft in axial

- 50 driving engagement with said timer shaft and extending through said bore, a support for said stub shaft, a braking member on said stub shaft adapted to engage said support in one position of the stub shaft, means normally holding said stub shaft in braking position, a clutch member on said stub shaft adapted to engage the shaft driving gear in a second and axially displaced position of the stub shaft and intermittently operable clutch engaging means adapted to force the stub shaft into engagement with the shaft driving gear and to release the braking member from engagement with the support.

4. In a timing apparatus having an intermittently rotatable timer shaft, cam means affixed to said shaft and a switch adjustable in position with respect to said cam and operable thereby, the improvement comprising, means for controlling rotation of said shaft and including, a constant speed motor having a shaft driving gear adapted to rotate continuously, a reciprocable

- 70 stub shaft in axial driving engagement with said timer shaft, a support for said stub shaft, a braking member on said stub shaft adapted to engage said support in one position of the stub shaft, spring means adjustably mounted on said

support in anti-friction force transmitting relation to said braking member for normally holding said stub shaft in braking position, a clutch member on said stub shaft adapted to engage the shaft driving gear in a second and axially displaced position of the stub shaft and intermittently operable clutch engaging means adapted to force the stub shaft into engagement with the shaft driving gear and to release the braking member from engagement with the support.

WILSON M. POWELL.
